CLAIM

I claim the ornamental design for a therapeutic bonding mitt, as shown and described.

DESCRIPTION

FIG. 1 is a perspective view of an embodiment of the therapeutic bonding mitt;

FIG. 2 is a side view of a first side of the therapeutic bonding mitt of FIG. 1;

FIG. 3 is a side view of a second side of the therapeutic bonding mitt of FIG. 1;

FIG. 4 is a side view of a third side of the therapeutic bonding mitt of FIG. 1;

FIG. 5 is a side view of a fourth side of the therapeutic bonding mitt of FIG. 1;

FIG. 6 is a top view of the therapeutic bonding mitt of FIG. 1; and,

FIG. 7 is a bottom view of the therapeutic bonding mitt of FIG. 1.

The broken lines in the drawings illustrate portions of the therapeutic bonding mitt which form no part of the claimed design.

1 Claim, 7 Drawing Sheets
